UNITED STATES PATENT OFFICE.

JOSEPH M. KAISER, OF CHICAGO, ILLINOIS.

ARTICLE-HOLDER.

1,155,581.

Specification of Letters Patent.

Patented Oct. 5, 1915.

Application filed May 15, 1915. Serial No. 28,240.

To all whom it may concern:

Be it known that I, JOSEPH M. KAISER, a citizen of the United States, residing at Chicago, in the county of Cook and State of Illinois, have invented a new and useful Improvement in Article-Holders, of which the following is a specification.

I have devised my invention for use more particularly in cases for toilet-articles commonly provided in a form suitable for use by travelers and of the type involving one or more series of loops which serve to hold the articles in spaced relation in position in the case; and my objects, generally stated, are 10 to provide, in holders of the type above referred to, improvements of a novel and simple character to the end that they shall be adapted to firmly secure in the case, against accidental displacement, articles of 15 different kinds and sizes; and permit of the ready adjustment of the loop-forming members.

Referring to the accompanying drawings, Figure 1 is a face view of a toilet-article-holding case constructed in accordance with my invention, showing the articles in place. Fig. 2 is an enlarged broken section taken at the line 2 on Fig. 1 and viewed in the direction of the arrow, the articles being 20 omitted. Fig. 3 is a plan view of the strip which is secured to the body of the case and provides the spaced loops through which the loop-forming strap is threaded. Fig. 4 is a section taken at the line 4 on Fig. 2 and 25 viewed in the direction of the arrow, the loop-forming strap being shown as drawn down into engagement with the strip, to the position shown by dotted lines in Fig. 2; and Fig. 5, an edge view of the structure 30 shown in Fig. 2 viewed from the right-hand end of this figure.

The general characteristics of the case in connection with which I have chosen to illustrate my invention, are the same as the ordinary form of traveling article-supporting case, involving a body-section 6 formed of two sections 7 and 8 of any suitable material, as, for example, cloth, sewed together along three sides of the section 8 which 40 leaves one edge of this section free, as represented at 9 and forms a pocket, the opposite ends of the section 7 where they extend beyond the section 8 forming pocket-containing flaps 10 and 11, which, with flaps 12 and 13 carried by the section 6 at angles to the flaps 10 and 11, serve, when folded 45 into superposed position on the section 6, to close the case and inclose therein the articles held in the case as hereinafter referred to.

In the particular construction of traveling case illustrated two series of loop-forming devices are provided to hold in the case both small articles and relatively long ones, in the case of the latter the articles being held 50 at their opposite ends in the loops at opposite ends of the case. The loop-forming devices referred to are of the same construction, each being constructed in accordance with, and presenting the preferred embodiment of, my invention, a description of these devices being as follows: Sewed, or otherwise secured, to the face of the section 8, are strips 14 of any suitable material, as for example leather, presenting at intervals 55 transversely extending loops 15, these loops, by preference, being integral with the strips 14. Straps 16 of leather, or any other suitable material, and each secured at one end to the case, as by the stitching, represented 60 at 17, which penetrates the sections 7 and 8 of the case, the strips 14 and the straps 16, and secures these parts together, are passed under the loops 15 of the respective strips 14, as represented in the drawings, to provide the loops 18, into which loops the articles to be held in the case are inserted, as 65 shown in Fig. 1. The straps 16 are free to slide in the loops 15 and may be drawn taut over the articles inserted into the loops 18, 70 whether or not all the loops 18 are filled. The straps 16 are of sufficient length to extend at their free ends beyond the free edge 75 of the section 8 when the straps are drawn taut over the articles inserted into the loops 18, and after drawing them to taut condition, by pulling on their free ends, are turned 80 rearwardly and over the edge 9 and tucked at their extremities, to overlap the underside of the section 8, into slots 20 formed in the 85 section 8, as shown in Fig. 1, these slots, in the preferred construction, being formed by securing loops to the underside of the section 8, as shown. The free ends of the straps will thus be frictionally held against 90 slippage and the articles in the loops 18 held against accidental displacement. The loop 95 15 nearest the edge 9 in the case of each strip 14, and the loops 20, are preferably so disposed that the marginal edge-portion 9 100 of the section 8 will extend beyond them a slight distance, as for example about one-

eighth of an inch, which causes the portions of the edge 9 engaged by the straps 16 to turn back slightly when the extremities of the straps are drawn taut, and thus the frictional grip between the straps and the parts they engaged, is enhanced.

Under some conditions of use the straps may, at certain portions thereof, be drawn taut between adjacent loops 15, with no article held thereby at such portions, in which case, where the loops 15 are held in place by side strips, as for example in the particular construction of the strip 14 illustrated, provision, by preference, should be made for holding such portions of the straps a slight distance away from the section 8, in order that the operator may readily grasp the edges of the straps and pull the straps to form loops at those portions, where desired. In the construction illustrated this is accomplished by providing the strips 14, in the spaces between adjacent loops 15, with projections 21, preferably integral, with the strips 14 and extending in overlapping position relative to the straps which pass under the loops 15, and thus should a portion of a strap be drawn taut between adjacent loops 15, as illustrated by dotted lines in Fig. 2, this portion will be held in such position that its free edge is accessible and permits the strap to be readily lifted and drawn through these loops 15 to form one of the loops 18, if desired at this point.

While I have illustrated and described a particular construction in which my invention is embodied, I do not wish to be understood as intending to limit it thereto, as the same may be variously modified and altered without departing from the spirit of my invention.

What I claim as new and desire to secure by Letters Patent, is:

1. An article-holder provided with loops on one face, a strap threaded through said loops and having a free end adapted to be deflected over an edge of the holder and turned back to oppose the opposite face of the holder, and means frictionally engaging the free end of the strap which is turned back and extends beyond said edge.

2. An article-holder provided with loops on one face, a strap secured at one end and having its free end threaded through said

loops and adapted to have its free end deflected over an edge of the holder and be turned back to oppose the opposite face of the holder, and means frictionally engaging the portion of the free end of the strap which is turned back and extends beyond said edge.

3. An article-holder provided with loops on one face of a section thereof and containing a slot, and a strap threaded through said loops and having a free end adapted to be deflected over an edge of the holder and be turned back to oppose the opposite face of the holder and be inserted into said slot.

4. An article-holder provided with loops on one face of a section thereof and with a loop on the rear face of said section, and a strap threaded through said first-named loops with its free end adapted to be deflected over an edge of said section and be turned back and inserted into said loop.

5. An article-holder provided with loops on one face of a section thereof and with a loop on the rear face of said section, one of said first-named loops and said last-named loop being located closely adjacent to an edge presented by said section, and a strap threaded through said first-named loops with its free end deflected over said edge and turned back and lying within said last-named loop.

6. An article-holder provided with loops with strips extending between said loops, and a strap threaded through said loops and slidable therein and located between said strips, and means for holding portions of the undersurface of the strap between said loops above the plane of the upper surfaces of said strips.

7. An article-holder provided with loops with strips extending between said loops, and a strap threaded through said loops and slidable therein and located between said strips, and projections on said strips between said loops and engageable by said strap when drawn taut for holding portions of the undersurface of the strap between said loops and above the plane of the upper surfaces of said strips.

JOSEPH M. KAISER.
